Anton Sova, Euclid, Ohio

Application March 23, 1939, Serial No. 83,802

To all whom it may concern:

Be it known that I, Anton Sova, a citizen of the United States, residing at 19531 Tyrone Avenue, in the city of Euclid, county of Cuyahoga, and State of Ohio, have invented a new, original, and ornamental Design for a Combination Picture and Music Record and Support for Same, of which the following is a specification, reference being had to the accompanying drawing, forming a part thereof.

Figure 1 is a front elevational view of a combination picture and music record and support for same embodying my new design, the dominant feature of which is a space for mounting a picture on a raised central portion of the support

which raised portion is encircled by a phonograph record.

Figure 2 is a vertical cross-sectional view of the same article taken along the lines 2—2 of Figure 1, and which view shows a perforated easel folded against the support; and

Figure 3 is a side elevational view of the same showing the easel open on the back of the support.

I claim:

The ornamental design for a combination picture and music record and support for same, substantially as shown and described.

ANTON SOVA.
